UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

DIE-STOCK.

1,228,955.

Specification of Letters Patent.

Patented June 5, 1917.

Application filed March 6, 1917. Serial No. 152,458.

To all whom it may concern:

Be it known that I, IRA W. NONNEMAN, a citizen of the United States, residing at Warren, in the county of Trumbull and State of Ohio, have invented a certain new and useful Improvement in Die-Stocks, of which the following is a full, clear, and exact description, reference being had to the accompanying drawings.

10 This invention relates to die stocks adapted to cut tapered threads. The object is to provide very simple mechanism carried by the rotating member which carries the thread-cutting chasers, to effect a recession of such 15 chasers as the thread progresses, thus enabling a tapered thread to be efficiently and readily cut.

In accomplishing this controlled recession of the chaser, I provide a controlling 20 device on the chaser-carrying frame which engages in the thread which has just been cut, and, by moving radially in the frame, coacts with certain mechanism to allow a corresponding recession of the chaser. My 25 die stock is therefore self-receding in its nature, the chaser being allowed to play back according to the thread which it has itself cut. My invention includes such characteristic broadly and also the more specific features of it, as shown in the drawings hereof and as hereinafter more fully explained. The essential characteristics of the invention 30 are summarized in the claims.

In the drawings, Figure 1 is a front elevation of my die stock; Fig. 2 is an edge view thereof; Fig. 3 is an enlarged section substantially on a radial plane alongside one of the chasers; Fig. 4 is an enlarged fragmentary view of the face of the die stock with 40 the front plate removed, showing the parts in the position they occupy before the cutting begins; Fig. 5 is a view of the chaser, the follower, and the abutments detached from the frame and located in a receded 45 position; Fig. 6 is a somewhat diagrammatic view similar to Fig. 5, but with the parts in initial position; Fig. 7 is a fragmentary view of a portion of the frame with the parts removed; Figs. 8 and 9 are cross sections 50 through the frame and the chasers, as indicated by the lines 8--8 and 9--9 respectively on Fig. 4; Fig. 10 is a perspective view of one of the abutment blocks removed.

As shown in the drawings, 1 indicates a

revolute frame having an extended guiding sleeve 2 adapted to carry a bushing 3 surrounding the pipe. The frame is provided with the usual sockets 4, for the reception of handles 5, enabling it to be turned. In the frame are radial guideways 6, and these are covered by plates 7 secured to the frame by screws 8.

In the radial guideways are chasers 10, of the form shown particularly in Fig. 3. Each chaser has an inner tapered cutting edge 11 and its outer portion is cut away as shown at 12, providing reduced extensions. The cutting away to make these reduced extensions is done in two planes at an angle to each other to make a V-shaped shoulder 15 on the chaser, as indicated at 15.

20 indicates a follower mounted alongside of the chaser. The follower is wider than the chaser, as shown at 21, and occupies an enlarged recess 9 in the frame just outside 75 of the chaser-carrying guideway. The inner edge 23 of this follower is formed to enter the thread-groove cut by the chaser but is rounded at its extreme edge so that it cannot itself cut the pipe. The follower is provided 80 with a V-shaped head 25 at a similar angle to the shoulder 15 formed on the chaser. The follower and chaser are capable of some independence of movement and both 85 coact with the abutment, hereinafter described.

30 indicates the abutments, of which there are two for each chaser, and which coact therewith and with the follower to control the recession of the chaser. These 90 abutments are of the form shown perspective in Fig. 10. Each consists of a partially cylindrical block 30 mounted in a cavity 39 in the frame so that it may turn about its axis as if pivoted on such axis. The abutment has a cut-away edge 31 providing a shoulder 32 against which the inclined shoulder 15 on the chaser bears. Another cut-away portion 33 of the abutment provides a shoulder 34 which bears against the inclined head 25 of the follower. 35 is still another cut-away portion of the abutment, providing a recess for a spring to seat. 40 indicates such a spring, these being set into cavities 41 in the frame and tending to 105 swing that end of the abutment block toward the chaser.

It will be seen particularly from Fig. 6,

that in the position of the parts where the cutting begins the shoulder 32 engages the chaser shoulder 15 at such point that the thrust indicated by the line x from the point 32 to the center c of the abutment, is very nearly at right angles to the plane on the shoulder of the chaser. In other words, the thrust from the chaser against the abutment is substantially normal to the plane 10 of the chaser shoulder. Accordingly the abutment absolutely stops the chaser and may not be moved by the chaser. On the other hand, the normal line y from the follower shoulder 25 at the point of chaser 15 engagement at 34, passes to the outer side of the center of the abutment, and leaves a rotative component indicated by z in the diagram of forces, and thus the action of the chaser on the shoulder 34 tends to turn the abutment outwardly at that point against the action of the spring 40. Such outward turning carries the abutment shoulder 32 downwardly on the V-shaped shoulder of the chaser, and thus allows that chaser to 25 play back correspondingly.

It results from the construction described, that, while the chaser cannot itself shove back against the abutment, the follower may turn the abutment to allow the chaser to 30 play back according to the amount that the follower moves, since the inclines on the head of the follower and on the shoulder of the chaser are at the same angle. Now as the chaser starts to cut a tapered thread 35 on the pipe A, for example, the follower travels immediately afterward in adjacent threads, and not having a cutting inner edge, it is gradually forced outward by the thread which the chaser has cut, and in such 40 outward movement of the follower the abutments are swung against the action of their springs to correspondingly release the chaser so that it recedes outwardly. Therefore, the chaser gradually recedes under the 45 control of the thread which it has itself cut, or, in other words, the mechanism described provides what may be called a "self-receding" die stock.

It is to be understood that the actual 50 amount of recedence required is comparatively small, and the abutments may not swing as far as shown in Fig. 5. They never swing far enough in normal operation for the line of thrust of the chaser 55 against the abutment to become oblique enough for the chaser itself to move the abutment. It may be noted, however, that the springs increase in force as the abutment swings outwardly, which compensates 60 to a certain extent for the increasing obliqueness of the line of thrust of the shoulder, and this line may be somewhat oblique before the abutment could be moved by the chaser. The point where the abutments 65 could be moved by the chaser is not reached

in the normal recedence of the chaser, while the engagement of the follower is always effective to move the abutments.

50 in the drawings indicates a pair of stopping pins carried by the front frame 70 plate 7 and standing in the path of the cut-away portion 33 of the abutments, limiting the inward movement of the abutments under the action of the springs. It is desirable to limit the independence of movement between the follower and the chaser. To accomplish this I have provided a lug 75 18 on the chaser, entering a notch 28 in the follower, Fig. 3. Any suitable detent prevents the chaser inadvertently dropping out, 80 as for example, the plunger 60 pressed by a spring 61 against the chaser.

It will be seen that the die stock above described is very simple in construction and accomplishes the desired recedence of the 85 chasers without the necessity of a separate controlling member, either clamped to the pipe or abutting the end of the pipe, as has been heretofore customary. By controlling the recedence of the chaser by abutments 90 which are themselves moved by a follower, all mounted in the single rotating frame, I simplify the construction and render it more compact.

Having thus described my invention, what 95 I claim is:

1. A device for cutting tapered threads comprising a frame, a recessive chaser carried thereby, and means engaging the thread cut by the chaser for controlling the recession of the chaser. 100

2. The combination of a rotatable frame, a chaser movably mounted therein, and mechanism adapted to engage the thread being cut on a pipe and revolve about the 105 axis thereof as said frame revolves, said mechanism controlling the recession of the chaser.

3. In a die stock, the combination of a revoluble frame, a recessive chaser carried 110 thereby and formed to cut a tapered thread, a device revoluble with the chaser and adapted to successively engage each turn of the thread without cutting it after the chaser has completed its cut of such turn, and mechanism controlled by said device for limiting the recession of the chaser. 115

4. The combination of a revoluble frame, movable chasers therein, followers movably mounted along the outer side of the chasers 120 and adapted to engage the thread cut, and means controlled by said followers for limiting the recession of the chasers.

5. In a die stock, the combination of a revoluble chaser frame, a chaser carried 125 thereby and formed to cut a tapered thread, a movable abutment for the chaser, and a device carried by the frame and adapted to engage the thread cut by the chaser and operating to move said abutment. 130

6. In a die stock, the combination of a revoluble frame, a chaser movably carried therein and having teeth for cutting a tapered thread, an abutment holding said 5 chaser against movement away from the material being threaded, a follower lying alongside of the chaser and adapted to engage the thread which the chaser has cut, and means whereby the recession of the following lower causes a movement of the abutment to enable recession of the chaser.

7. In a die stock, the combination of a revoluble frame, a chaser radially mounted therein and having taper-cutting teeth at 15 its inner end, a bar lying parallel with the chaser radially in the frame and having a non-cutting end adapted to occupy the thread cut by the chaser, and a movable abutment mounted in the frame and limiting the outward movement of the chaser and 20 itself moved by the outward movement of the bar.

8. In a die stock, the combination of a revoluble frame, a chaser movably mounted 25 therein and provided with teeth for cutting a tapered thread, an actuating bar movably mounted in the frame and having a non-cutting edge adapted to engage the thread cut by the chaser, an abutment comprising 30 a block rotatively mounted in the frame and having a shoulder limiting the outward movement of the chaser and another shoulder adapted to be engaged by said bar.

9. In a die stock, the combination of a 35 revoluble frame, a chaser carried thereby and formed to cut a tapered thread, a movable abutment for the chaser, a device carried by the frame and adapted to engage the thread cut by the chaser and be moved thereby, means whereby such movement 40 moves the abutment to correspondingly release the chaser, and a spring acting on the abutment and tending to prevent such movement.

45 10. In a die stock, the combination of a revoluble frame, a chaser radially mounted therein and having tapered teeth at its inner edge, a bar lying parallel with the chaser radially in the frame and having a non-cutting edge adapted to occupy the thread cut by the chaser immediately following the chaser, a movable abutment mounted in the frame and limiting the outward movement 50 of the chaser and itself moved by the outward movement of the bar, and a spring tending to hold the abutment against such movement.

60 11. In a die stock, the combination of a revoluble frame, a chaser carried thereby, an actuating bar carried by the frame and adapted to engage the thread cut by the chaser, an abutment carried by the frame in position to turn on an axis, said abutment having two shoulders, one of which is adapted to be engaged by said actuating bar

whereby the abutment may be turned, said other shoulder limiting the outward movement of the chaser, and a spring acting on said abutment and tending to prevent the turning described.

70 12. In a die stock, the combination of a revoluble frame, a chaser movably mounted therein and provided with teeth for cutting a tapered thread and having a V-shaped shoulder, a pair of abutment blocks 75 rotatively mounted in the frame and each having a shoulder engaging said V-shaped shoulder and limiting the outward movement of the chaser, and an actuating device for said blocks movably mounted in the frame and having a non-cutting edge adapted to engage the thread cut by the chaser.

80 13. In a die stock, the combination of a revoluble frame, a chaser mounted therein and having a V-shaped shoulder, two rotative abutments each having a shoulder engaging such V-shaped shoulder on the chaser, an actuating bar carried by the frame and lying alongside of the chaser and having a V-shaped shoulder, and shoulders 90 on the abutments engaging the shoulder of the actuating bar, the abutment radius at the shoulder which engages the chaser being substantially perpendicular to the chaser shoulder, while the radius at the shoulder 95 which engages the bar is more oblique thereto.

14. In a die stock, the combination of a revoluble frame, a chaser mounted therein and having a V-shaped shoulder, two rotative abutments having shoulders engaging such V-shaped shoulder, an actuating bar carried by the frame and lying alongside of the chaser and having a V-shaped end, 100 shoulders on the abutments engaging the end of the actuating bar, and a pair of springs mounted in the frame and bearing against said abutments and pressing them toward the chaser.

105 15. In a die stock, the combination of a frame, a radial guideway therein, a chaser occupying said guideway, a pair of partial cylindrical recesses on opposite sides of the guideway, a pair of rotative abutments occupying said recesses, said abutments being provided with shoulders which engage a V-shaped shoulder on the chaser in a direction to take the thrust nearly through the center of the abutment, compression springs occupying recesses in the frame and bearing 110 against shoulders on the abutments for swinging the chaser-engaging edges toward the chaser, and an actuator for said abutments carried by the frame and provided with a non-cutting edge adapted to occupy 115 the thread cut by the chaser.

120 16. In a die stock, the combination of a frame, a radial guideway therein, a chaser occupying said guideway, a pair of partial cylindrical recesses on opposite sides of the 130

guideway, a pair of rotative abutments occupying said recesses, said abutments being provided with shoulders which bear against a V-shaped shoulder on the chaser in a direction nearly normal thereto, compression springs occupying recesses in the frame and bearing against shoulders on the abutments for swinging the chaser-engaging edge toward the chaser, and an actuating bar carried by the frame alongside of the chaser, said bar having a V-shaped head adapted to engage oblique shoulders on the abutments, the inner end of said bar being provided with a non-cutting edge adapted to occupy 15 the thread cut by the chaser.

17. A device for cutting tapered threads, comprising a frame, a movably mounted thread-cutting chaser therein, a movably mounted non-cutting follower in the frame 20 adapted to engage the thread cut by the

chaser, and means carried by the frame and controlling the position of the chaser and adapted to be moved by the follower but immovable by the chaser itself.

18. In a die stock, the combination of a 25 rotary frame, a set of chasers radially mounted in the frame and having thread-cutting teeth, a set of followers movably mounted in the frame, there being one follower for each chaser and the follower being provided with an edge adapted to engage the thread cut by the chaser without itself cutting, a series of movable abutments carried by the frame and controlling the 30 position of the chaser, and means whereby 35 said abutments may be moved by the followers but cannot be moved by the chasers.

In testimony whereof, I hereunto affix my signature.

IRA W. NONNEMAN.
